US00D814456S

(12) **United States Design Patent** (10) Patent No.: **US D814,456 S**
(45) Date of Patent: ** Apr. 3, 2018

(54) **ELECTRONIC DEVICE**

- (71) Applicant: **Samsung Electronics Co., Ltd.**, Suwon-si (KR)
- (72) Inventors: **Xiangrong Zhang**, Shanghai (CN); **Chen Cui**, Shanghai (CN); **Shiuan-Hung Lee**, Shanghai (CN); **Miika Johannes Mahonen**, Shanghai (CN)
- (73) Assignee: **Samsung Electronics Co., Ltd.**, Suwon-si (KR)
- (**) Term: **15 Years**
- (21) Appl. No.: **29/583,953**
- (22) Filed: **Nov. 10, 2016**

(30) **Foreign Application Priority Data**

(57) **CLAIM**

We claim the ornamental design for an electronic device, as shown and described.

DESCRIPTION

FIG. 1 is the front perspective view of an electronic device showing our new design;

FIG. 2 is the front view thereof;

FIG. 3 is the rear view thereof;

FIG. 4 is the left-side view thereof;

FIG. 5 is the right-side view thereof;

FIG. 6 is the top view thereof;

FIG. 7 is the bottom view thereof; and,

FIG. 8 is the rear perspective view thereof.

The broken lines depict portions of the electronic device that form no part of the claimed design.

1 Claim, 7 Drawing Sheets
